UNITED STATES PATENT OFFICE.

JAMES G. BLUNT, OF SCHENECTADY, NEW YORK.

CYLINDER COCK.

Application filed March 13, 1925. Serial No. 15,400.

This invention relates to a combined cylinder cock and automatic water relief valve for locomotives.

One of the objects of my invention is to provide in a device of such character a valve which will open automatically when the locomotive is at rest, to drain off the water of condensation from the locomotive cylinder and which may be opened at other times, by manually controlled means, for the same purpose.

Another object is to provide in such a device a separate valve which is adapted to be opened automatically by an excess of pressure in the locomotive cylinder, caused, for example, by an accumulation of water therein, and which, upon being opened, relieves the pressure and permits the accumulated water to drain off.

A further object of my invention is to combine these two valves in a single housing, so that while the outlet openings which they control are separate, a single inlet, or communication to the cylinder, may be employed for both.

Another object of my invention is so to dispose the valve controlled outlets to which I have referred that the escape of moisture and steam through them will be muffled.

Preferably, also, I provide means which may be used, when desired, for securing the water-relief-valve in closed position, so that it will not operate, such means, however, not affecting the cylinder-cock-valve in any way.

Other objects of my invention will appear more fully hereinafter.

In the drawings, Fig. 1 is a longitudinal cross section of my improved device, both the cylinder-cock-valve and the water-relief-valve being closed; Fig. 2 is a similar view, showing the cylinder-cock-valve in the open position which it assumes when the locomotive is at rest; Fig. 3 shows the water-relief-valve, as it is opened automatically by an excess of pressure in the locomotive cylinder; and Fig. 4 is a fragmentary view showing the end cover of the casing reversed so that it holds the water-relief-valve positively closed.

The housing 1 is preferably of a generally cylindrical form. Within it is a chamber 2 which communicates with the locomotive

cylinder through the inlet 3. This chamber 2 is provided at the left with two separate outlets, each controlled by its own valve, namely, the outlet 4 (which may consist of a number of radial openings, as shown in the drawing) and the outlet 5. The outlet 4 is normally closed by the cylindrical valve 6, which I shall call the cylinder-cock-valve, and the outlet 5 is normally closed by the annular valve 7, the water-relief-valve.

I shall now describe the means for controlling and operating the cylinder-cock-valve 6. This valve constitutes a part of the differential piston 6, 8, 9, the area of the end 9 being greater than that of the end 6. A spring 10 normally tends to push this piston to the left to open the valve 6. But when the locomotive is in operation, with steam in its cylinders, steam pressure is communicated to the chamber 2 through the inlet 3. This pressure, acting on the differential piston, holds it in the position shown in Fig. 1, against the action of the spring 10.

When the locomotive comes to rest the steam pressure in its cylinder is reduced, and, as a result, the spring 10 pushes the differential piston to the left to open the valve 6, and permit the water of condensation to drain off. When steam is again admitted to the locomotive cylinder, to set the locomotive in motion, pressure is again built up in chamber 2 sufficient to move the differential piston to the right to close the valve 6.

In addition to this automatic arrangement for operating the valve 6, I provide manually controlled means for opening the valve 6, when desired, while there is steam pressure in the cylinder and in the chamber 2. These means include the auxiliary piston 11 against which one end of the spring 10 seats. Fluid under pressure, as for example, air from the air-brake supply, may be admitted behind this auxiliary piston through the inlet 12, when desired, by means of a control (not shown) located in the cab. The effect is to push the auxiliary piston 11 to the left, compressing the spring 10 and causing it to overcome the differential action of the steam pressure in the chamber 2 and to open the valve 6. Any air leaking between the piston 11 and its cylinder will escape through the ports 11a.

All movements of the valve 6 and of the

valve 7 are cushioned by the dash pot effect of the chamber 13 which is formed in the valve 7 and within which the valve 6 is slidably mounted. This chamber, which is 5 provided with leakports 13^a, operates alternately as a compression or vacuum chamber, as will be readily understood.

The valve 7, as shown, is concentric with the valve 6, and, in fact, forms the casing 10 or cylinder 13 in which that valve operates. In Fig. 1 the valve 7 is closed against its outlet seat 5, and held closed by the spring 15 against the steam pressure within the chamber 2. In this connection it should be 15 noted that in my construction, so far as the valve 7 is concerned, this steam pressure acts only upon the relatively small annular surface 7^a, and not upon a complete circular surface the size of the outlet 5. Therefore 20 the spring 15 for overcoming this pressure can be very much lighter than is required in the case of a water-relief-valve which is not combined with a cylinder-cock-valve in the manner described.

25 As stated, the spring 15 resists the normal steam pressure in the locomotive cylinder and chamber 2. But when there is an excess of pressure due to an accumulation of water in the cylinder, the spring 15 is 30 overcome and the valve 7 is opened, relieving the pressure and draining off the water through the outlet 5. When the pressure has been relieved sufficiently, the spring 15 again closes the valve.

35 The compression of the spring 15 may be 40 adjusted in any suitable way, as for example, by adding or removing washers 16. In case the spring 15 should break, or for any other reason it were desired to hold the valve 7 closed positively against automatic 45 operation, that can be accomplished by reversing the left hand end plate 17, as shown in Fig. 4.

Whichever of the valves 6, 7, is opened, 45 the escaping steam and water does not pass directly to the atmosphere but goes first into muffling chamber 18 from which it escapes through the numerous small ports 50 18^a. The effect of this is to reduce materially the noise incident to the operation 55 of the device.

From the above description it will be 55 apparent that I have produced a simple and efficient cylinder cock and relief valve, 60 all of the parts of which are conveniently assembled within a single housing, but in such a way that the two valves operate independently of each other, though communicating with the locomotive cylinder 65 through a single inlet.

The terms and expressions which I have 65 employed are used as terms of description and not of limitation, and I have no intention, in the use of such terms and expressions, of excluding any equivalent of the

features shown and described, or portions thereof, but recognize that various modifications are possible within the scope of the invention claimed.

What I claim is:

1. In a cylinder cock structure for steam locomotives, an elongated casing having a steam inlet port in its side wall, a differential piston device mounted in the casing for movement longitudinally thereof, hollow cylindrical seats for the pistons of said differential piston device, the seat for the smaller piston being provided in its side wall with a discharge port adapted to be covered and uncovered by the movement of the piston, said steam inlet port in the casing being located between the pistons whereby steam pressure will act on the larger piston to move the smaller piston to port closing position, and spring means acting against the outer end of the larger piston to move the smaller piston to discharge port uncovering position upon the fall of steam pressure between the pistons. 70

2. In a cylinder cock structure for steam locomotives, an elongated casing having a steam inlet port in its side wall, a differential piston device mounted in the casing for movement longitudinally thereof, hollow cylindrical seats for the pistons of said differential piston device, the seat for the smaller piston being provided with a discharge port adapted to be covered and uncovered by the movement of the smaller piston, said steam inlet port in the casing being located between the pistons whereby steam pressure will act on the larger piston to move the smaller piston to discharge port closing position, spring means acting against the outer end of the larger piston to move the smaller piston to discharge port uncovering position, and manually controlled pneumatic means arranged to act on the differential piston to move the smaller piston to discharge port uncovering position. 90

3. In a cylinder cock structure for steam locomotives, an elongated casing having a steam inlet port in its side wall, a differential piston device mounted in the casing for movement longitudinally thereof, hollow cylindrical seats for the pistons of said differential piston device, the seat for the smaller piston being provided with discharge ports adapted to be covered and uncovered by the movement of the piston, said steam inlet port in the casing being located between the pistons whereby steam pressure will act on the larger piston to move the smaller piston to discharge port closing position, spring means acting against the outer end of the larger piston to move the smaller piston to discharge port uncovering position upon the fall of pressure between the pistons, and a muffling chamber so arranged with relation 115

to the discharge ports that discharging fluid passes therethrough whereby to muffle the noise of discharge.

4. In a cylinder cock structure for steam locomotives, an elongated casing having a steam inlet port in its side wall, a differential piston device mounted in the casing for movement longitudinally thereof, hollow cylindrical seats for the pistons of said differential piston device, the seat for the smaller piston being provided in its side wall with a discharge port adapted to be covered and uncovered by the movement of the smaller piston, said steam inlet port in the casing being located between the pistons whereby steam pressure will act on the larger piston to move the smaller piston to port closing position, spring means acting against the outer end of the larger piston to move the smaller piston to discharge port uncovering position upon the fall of steam pressure between the pistons, said seat for the smaller piston serving also as an annular valve member, a seat for the annular valve member adapted to be engaged by the inner end of the annular valve, and spring means engaging the annular valve member and tending to hold the same against its seat, a portion of the end of the annular valve being exposed to pressure whereby excessive pressure between the pistons will move the annular valve member from its seat.
5. In a cylinder cock structure for steam locomotives, an elongated casing having a steam inlet port in its side wall, a differential piston device mounted in the casing for movement longitudinally thereof, hollow cylindrical seats for the pistons of said differential piston device, the seat for the smaller piston being provided with a discharge port adapted to be covered and uncovered by the movement of the smaller piston, said steam inlet port in the casing being located between the pistons whereby steam pressure will act upon the larger piston to move the smaller piston to discharge port closing position, spring means acting against the outer end of the larger piston to move the smaller piston to discharge port uncovering position, manually controlled pneumatic means arranged to act on the differential piston to move the smaller piston to discharge port uncovering position, said seat for the smaller piston serving also as an annular valve member, an annular seat for the annular valve member adapted to be engaged by the inner end of the annular valve member, a radially extending flange on the annular valve member, spring means engaging the flange and tending to hold the annular valve member against its seat, a portion of the inner end of the annular valve member being exposed to pressure whereby excessive pressure between the pistons will move the annular valve member from its seat, and a muffling chamber so arranged with relation to the discharge port that discharging fluid passes therethrough whereby to muffle the noise of discharge.

5. In a cylinder cock structure for steam locomotives, an elongated casing having a steam inlet port in its side wall, a differential piston device mounted in the casing for movement longitudinally thereof, hollow cylindrical seats for the pistons of said differential piston device, a seat for the smaller piston for the annular valve member adapted to be engaged by the inner end of the annular valve member, and spring means engaging the annular valve member and tending to hold the same against the seat, a portion of the end of the annular valve member being exposed to pressure whereby excessive pressure between the pistons will move the annular valve member from its seat.

6. In a cylinder cock structure for steam locomotives, an elongated casing having a steam inlet port in its side wall, a differential piston device mounted in the casing for movement longitudinally thereof, hollow cylindrical seats for the pistons of said differential piston device, a seat for the smaller piston being provided with a discharge port adapted to be covered and uncovered by the movement of the smaller piston, said steam inlet port in the casing being located between the pistons whereby steam pressure will act upon the larger piston to move the smaller piston to discharge port closing position, spring means acting against the outer end of the larger piston to move the smaller piston to discharge port uncovering position, manually controlled pneumatic means arranged to act on the differential piston to move the smaller piston to discharge port uncovering position, said seat for the smaller piston serving also as an annular valve member, an annular seat for the annular valve member adapted to be engaged by the inner end of the annular valve member, a radially extending flange on the annular valve member, spring means engaging the flange and tending to hold the annular valve member against its seat, a portion of the inner end of the annular valve member being exposed to pressure whereby excessive pressure between the pistons will move the annular valve member from its seat, and a muffling chamber so arranged with relation to the discharge port that discharging fluid passes therethrough whereby to muffle the noise of discharge.
